CLAIM

The ornamental design for a ceiling fan motor housing, as shown and described.

DESCRIPTION

FIG. 1 is a bottom and side perspective view of a ceiling fan motor housing showing my new design.

The broken line showing of environmental structure is for illustrative purposes only and forms no part of the claimed design;

FIG. 2 is an enlarged side elevational view thereof, the other side views being substantially identical; and

FIG. 3 is an enlarged top plan view thereof, the bottom plan view being substantially identical.

FIG. 1

FIG. 2

FIG. 3
